PERFORATING MACHINE

Reginald Theodore Firminger, London, England

Application September 22, 1950, Serial No. 186,256
In Great Britain February 10, 1948

5 Claims. (Cl. 197—6)

1

This invention relates to machines for perforating ribbon or like flat material with figures, letters or signs, and has for its object to provide a machine for such purpose operable by keys similar to a typewriter, whereby any number or arrangements of figures, letters, or signs can be perforated.

According to this invention, the machine comprises a set of keys and key actuated levers similar to a typewriter with one key and key actuated lever for each symbol to be perforated, and each lever carries at its end a perforated plate for action in conjunction with a perforating device in which the material to be perforated is located, incorporating a number of pins or punches arranged to cover the whole area of the largest symbol, each plate being perforated so that in operation the unwanted pins can pass through the perforations and the wanted pins are engaged by the solid part of the plate to punch the perforations required, power means for driving the machine, and means whereby on striking a key its plate is moved into position in the perforating device and held therein, the key action also starting power drive to perform the perforation and after perforation to release the perforated plate so that it and its key can return to normal position and release the power drive so that all parts return to normal.

Escapement means are provided for movement of the carriage.

The invention will be clearly understood from the following description aided by the accompanying drawings, in which:

Figure 1 is a front view of sufficient of a machine to show one example of carrying the invention into effect, Figure 2 is a section on the line II—II of Figure 1, Figures 3, 4 and 5 are views on the line III—III of Figure 2, Figure 6 is a side section of part of the perforating mechanism, and Figure 7 a section on the line VII—VII of Figure 2.

The invention can be carried into effect in various ways as to detailed construction.

In the example shown in the accompanying drawings, the machine comprises a frame 1 having an inner movable frame 2 carrying a number of keys 3 and key actuated levers 4 similar to a typewriter, the movable frame 2 being slideable to reciprocate up and down under action of an eccentric 5 mounted on a shaft 6 driven from a prime mover. A fixed block or frame 7 is provided on the frame 1 and a carriage 8 is movable across the machine.

Each key actuated lever 4 carries at its end a 55 escapement pawl 31, one end of which coacts

2

perforated plate 9 having on each side a notched recess 9a so that the end or nose of the plate 9 is somewhat of T shape.

On the movable frame 2 and at a position usually occupied by the operative part of the ribbon on a typewriter are positioned two pivoted levers 10, 11, having noses 10a, 11a, which project towards each other, with recessed portions 10b, 11b behind the noses 10a, 11a, said levers 10, 11 being spring controlled by springs 12 so that the noses 10a, 11a normally close towards each other. Between the pivoted levers 10, 11 is a lever 13 hingedly connected to a fixed block or member of the frame 1, said lever 13 being connected by a link 14 to a trip lever 15 pivotally mounted intermediate of its length, the lever 13 being spring controlled by a spring 16. A plate 17 having an opening shaped as a guide is positioned in front of the levers 10, 11. 20 On the movable frame 2 and in front of the two pivoted levers 10, 11 but at a lower plane is positioned a block or member 18 having a number of holes arranged close together and in lines, such holes covering an area as large as the largest letter, figure or sign to be perforated, and above said block 18 is another block 19 having a similar number of holes, the block 19 forming part of the frame 1, and in each hole is a pin or punch 20, and above the punch block 19 and at a little distance away is another block or anvil 21 also secured to the frame 1 and having holes corresponding to those in the block 19. The material 24 to be perforated passes between the top blocks 19, 21, the plates 9 on the key actuated levers 4 being adapted to enter between the lower block 18 and the punch block 19.

The drive shaft 6 carries a loose pulley wheel 22 which is driven from any suitable prime mover, a roller or other clutch 23 being provided for locking the pulley 22 to the shaft 6.

The clutch 23 is actuated by mechanism of any suitable kind on striking a key actuated lever 4 as will be hereinafter described.

The carriage 8 for supporting the material 24 comprises a frame which is provided with grooved wheels 25 riding on cross rails 26 and is spring urged in one direction.

The carriage 8 has depending arms 27 carrying a toothed rack 27a which co-operates with a pinion 28 mounted on a shaft 29 rotatably mounted in bearings in the main frame 1. The shaft 29 also carries a suitable toothed escapement wheel 30.

On the main frame 1 is rockably mounted an escapement pawl 31, one end of which coacts

with the escapement wheel 30 while the other end is acted upon by an arm 32 carried by the movable frame 2 and so arranged that as the movable frame 2 is raised and lowered, the pawl 31 is actuated to allow the carriage 8 to slide step by step under action of its spring similarly to an ordinary typewriter.

A second lever 33 is also provided pivotally mounted to the main frame 1 operable through a link 34 from a spacing bar 35 for action on the pawl 31 to allow the carriage 8 to be moved step by step independently of the movable frame 2.

The material 24, such as a coil of lead strip, is supported on a bracket 36 on the main frame 1 and is passed over a roller 37 and under a roller 37a on one end of the carriage 8 and through clamping devices 38, 39, one at each end of the carriage 8. The material 24 on the carriage 8 passes through between the top blocks 19, 21.

A cutting off device 40 is provided at the end of the carriage 8.

One member of the roller clutch 23 is provided with a cam plate 41 and the other member with a cam nose 41a. On the main frame 1 is pivotally mounted at 42 a clutch lever 43 located across the top of the cam plate 41, the lever 43 carrying a stop 44 and a downwardly projecting arm 45 having its end curved so as to be under the cam plate 41. The lever 43 with the arm 45 is normally urged upwards by a spring 46. The lower end of the trip lever 15 is adapted to engage with the end of the lever 43, as will be seen in full lines in Figure 7.

In normal condition, the inner movable frame 2 is in its lower position, with the hinged levers 10, 11 held open by the hinged lever 13 engaging in the recesses 10b, 11b in the levers 10, 11 (Figure 3) and with the pulley 22 being constantly rotated by the prime mover. The material 24 is in position for perforating, and when a key 3, say for the letter A, is depressed as in typing, the perforated plate 9 on the end of its lever is swung up and passes through the shaped guide 17 and strikes against the hinged lever 13 pivoting it on its hinge for its full movement so that it is free of the hinged levers 10, 11 which then partially close together under action of the spring 12 so that the noses 10a, 11a engage with the sides of the perforated plate 9. On removing the finger from the key 3 the perforated plate 9 will retract until the noses 10a, 11a engage in the recesses in the sides of the plate 9 and grip and hold the plate 9 in position between the lower block 18 and the block 19, as in Figure 5.

The pressing back of the hinged lever 13 actuates the trip lever 15 to allow the clutch lever 43 to rise so that its stop 44 is free of the nose 41a to allow the clutch 23 to come into action to engage the pulley wheel 22 with the shaft 6 so that the shaft 6 commences to revolve, the hinged lever 13 being held back by the clutch lever 43 engaging the trip lever 15. The shaft 6 through the eccentric 5 raises the movable frame 2 and with it the perforated plate 9, pins 20, and pivoted levers 10, 11, the hinged lever 13 not moving.

During this upward movement, the solid part of the perforated plate 9 will engage with the lower ends of the pins 20 necessary to form the letter A, such pins 20 being pushed upwards through the material 24 and anvil 21, and the holes in the perforated plate 9 will pass over the other pins 20 not required for the letter A, so that these pins 20 are not operated. The other perforated plates 9 operate similarly, the per-

forations being so arranged that only the necessary pins 20 for the letter or figure are engaged by the solid part of the plate 9.

When the shaft 6 has completed half a revolution the movable frame 2 will be at its highest point, and the nose 41a of the cam plate 41 acts on the arm 45 of the lever 43 to depress the arm 43 to allow the lever 15 to return to normal position. The hinged lever 13 will also return to its normal position under and clear of the hinged levers 10, 11, and the material 24 will have been perforated.

During the second half revolution of the shaft 6, the movable frame 2 will descend and the top end of the hinged lever 13 will engage between the inner faces of the levers 10, 11, and as the movable frame 2 reaches its lowest position, the hinged lever 13 will open the levers 10, 11 so as to free the perforated plate 9 and allow the plate 9 and key actuated lever 4 to return to normal position under action of a spring (not shown). The pins 20 which are slidably held in the block 19 will be returned to normal position clear of the perforated plate 9. The hinged lever 13 has a wedge action in opening the levers 10, 11. As the shaft 6 completes its revolution, the cam nose 41a engages the stop 44 and allows the clutch 23 to return to normal under action of a spring (not shown) so that the pulley wheel 22 is again free on the shaft 6 and the shaft 6 is stopped until another key is depressed to start a new cycle of operations.

As soon as the pins 20 have left the material 24 being perforated the tooth wheel 30 and escapement mechanism is operated by the arm 32 to allow the carriage 8 to move forward one step under its spring ready for the next perforation.

Preferably means are provided for locking all the keys except the key which has been operated. A convenient means comprises locating an inverted channel shaped member under a slidable link (not shown) connecting each key to its key actuated lever. On each link is a depending nose-shaped plate. The channel shaped member is pivotally mounted at its ends near the rear flange so that it normally tends to rock downwards at the forward edge clear of the nose-shaped plates. The parts are so arranged that on striking a key, the link of that key moves backwards and its nose-shaped plate engages the rear flange of the channel shaped member and rocks same backwards so that the front flange moves up to the rear of the nose-shaped plates of all the other links and prevents the other keys being depressed. On return of the actuated key, the channel shaped member returns to normal position.

The invention is suitable for perforating any ribbon or like flat material which can be perforated, and is especially useful for perforating lead and other strip or ribbon, in which case the strip or ribbon may, as already described, be wrapped on reels held by a bracket 36 provided on the outer frame 1.

Various modifications and detail alterations may be made.

What I claim as my invention is:

1. A machine for perforating ribbon and like flat material with figures, letters or signs, comprising a perforating device in which the material to be perforated is positioned, said perforating device including a set of pins arranged to cover the whole area of the largest sign, a set of keys and key actuated levers, one key and one

key actuated lever being provided for each sign to be perforated, a perforated plate carried by each key actuated lever and movable thereby into operative position in the perforating device for cooperation with said pins, means for holding each perforated plate in such operative position during a perforating operation, each of said plates having perforations therein arranged for passage therethrough of the unwanted pins and for engagement by the solid part of the plate with the wanted pins to punch the required perforations, a movable frame operative to advance a perforated plate into cooperation with the pins of the perforating device for performance of a perforating operation, power means for advancing and retracting the movable frame, controlling means for starting and stopping the power means, and means operative upon said controlling means in response to actuation of each key to start the power means and thereby advance the movable frame to move the respective perforated plate into cooperation with the pins of the perforating device to perform a perforating operation, said controlling means being operative upon completion of the perforating operation to stop the power means after retraction of the movable frame and to actuate the holding means to release the perforated plate and permit return of said plate and its key to normal condition.

2. A machine for perforating figures, letters or signs in ribbon or like flat material comprising a main frame, a vertically movable frame in said main frame carrying keys and key actuated levers similar to a typewriter, a main shaft carrying an eccentric adapted to raise and lower the movable frame, a carriage for the flat material movable across the main frame, spring means urging the carriage in one direction, escapement means controlled by the movable frame to allow the carriage to move step by step under the action of said spring means, a block having a number of holes on the movable frame, another block also having a number of coinciding holes secured to the main frame above the movable block, a pin in each of the coinciding holes in the fixed block, an anvil mounted on the main frame at a little distance above the fixed block and having holes coinciding with the holes in the fixed block and so positioned that the flat material carried by the carriage can pass through between the fixed block and the anvil, a perforated plate on each key actuated lever adapted to be located on striking a key, between the movable block and

the fixed block, means for holding the perforated plate in position during the perforating operation, a power drive connected through a clutch with the main shaft, means operated on striking a key to engage the clutch and drive the main shaft, and means for disengaging the clutch on completion of the perforation, the pins in the fixed block being arranged to cover the whole area of the largest symbol, and each plate being perforated so that in operation the unwanted pins can pass through the perforations in the plate and the wanted pins can be engaged by the solid part of the plate to punch the perforations required.

15 3. A machine for perforating ribbon or like flat material as claimed in claim 2, wherein the perforated plates on the key actuated levers are formed on each side with a notched recess so that the end of each plate is of T shape, and
20 wherein the holding means for the perforated plate is located between the movable block and the fixed block and comprises two pivoted levers having noses which project towards each other with recessed portions behind the noses, spring means to normally close the nose ends of the levers towards each other, a lever hingedly connected to the frame of the machine, the upper end of which is adapted to engage between the two pivoted levers, and a trip lever connected to the lower end of the hinged lever and adapted to actuate the clutch.

25 4. A machine for perforating ribbon or like flat material as claimed in claim 3, wherein the frame of the machine is provided with a bracket adapted to support a coil of flat strip material and the carriage is provided at each end with a clamp adapted to clamp a length of material from the coil on the carriage.

30 5. A machine for perforating ribbon or like flat material as claimed in claim 4, wherein the carriage is provided at the outward end with a cutting device for severing a length of perforated material after drawing through the carriage.
